UNITED STATES PATENT OFFICE.

JOHANNES MARINUS VAN DER POEL, OF EINDHOVEN, NETHERLANDS, ASSIGNOR TO
N. V. PHILIPS' GLOEILAMPENFABRIEKEN, OF EINDHOVEN, NETHERLANDS.

METAL VAPOR-JET PUMP.

Application filed November 11, 1924, Serial No. 749,357, and in the Netherlands May 8, 1924.

This invention relates to metal vapor jet pumps, more particularly to mercury vapor jet pumps but may also be applied for example to pumps operating with the vapor 5 of metals that have at ordinary temperatures a lower vapor pressure than mercury, such as lead, tin, bismuth, cadmium, zinc and the like.

Metal vapor jet pumps are hereinafter to 10 be understood to mean pumps that are constructed in such a manner that they are capable of operating against a comparatively poor prevacuum; for example, a pressure of 5 mm. or more.

15 It has already been proposed to construct mercury vapor jet pumps that have several stages. As a rule these pumps are provided with a central jet tube of circular section and with one or more annular jet tubes, 20 whilst the mercury vapor between two successive stages is condensed by cooling.

In such pumps the good operation depends 25 on the ratio of the vapor speeds in the several stages and it is therefore necessary that the once determined surfaces of the sections of the jet tubes be constantly maintained in the course of time, as otherwise the pump loses its good effect. In practice it occurs 30 that the size of the section of the jet tube is modified, owing to the precipitation of some substance or other on the walls of the jet tube near the outlet aperture and especially on the wall of the cooling vessel. This occurs, for example, in exhausting electric 35 vacuum lamps, the filaments of which are frequently sprayed with red phosphorus. During the exhaustion a little phosphorus vapor is carried along and phosphorus is precipitated in the pump, especially in the 40 said places. The operation of the pump diminishes and may even entirely cease.

Besides in pumps having several stages, 45 the said inconvenience may also present itself in pumps that operate with only one vapor jet.

The object of the invention is to construct 50 metal vapor jet pumps, more particularly mercury vapor jet pumps adapted to the exhaustion of electric incandescent lamps and the like, in such a manner that the pump 55 can easily be taken to pieces so that it is possible to clean its members, especially the jet tubes. Such a construction is possible if according to the invention in single- or

multi-stage metal vapor jet pumps, all stages 55 operate with annular vapor jets. The annular jet tubes are preferably arranged after each other around a common central vapor supply tube.

According to the invention, one or more 60 removable hoods forming with the tube downwardly directed annular jet tubes, may be arranged on the central vapor supply tube. The vessel that surrounds the annular jet tubes, is preferably so constructed above 65 the hoods that the latter can be removed in upward direction. According to the invention the cleaning of the pump may be facilitated still more by constructing the pump so as to allow the removal of the central vapor 70 supply tube with the jet tubes pertaining to it without further necessity of taking the pump to pieces.

According to the invention the vapor supply from the central vapor supply tube to 75 the successive jet tubes can be regulated by means of apertures provided in the wall of the central tube. The apertures for the vapor supply to the jet tube (tubes), lying on the high vacuum side of the pump, have 80 preferably a regulable size.

According to another characteristic of the invention, the mercury vapor jet pumps may be so constructed that they, after having been 85 filled with a gas of high pressure, can rapidly be put into service again without any risk of mercury flowing out of the pump.

Mercury vapor jet pumps can operate 90 against a comparatively poor prevacuum of, for example, 20-60 millimeters and the 95 pumps that have several stages, are able to reach a very high vacuum. Such pumps have the inconvenience that if for some reason or other, for example owing to a leak in the high vacuum conduit, the pump has been 100 filled with gas of high pressure and it is then put into service again, mercury is thrown out. This is caused by the sudden boiling up of the mercury when the gas pressure in the pump is suddenly reduced, after the latter has been filled with a gas of high pressure. An excessively large quantity of mercury 105 vapor is formed and, moreover, mercury from the receptacle is carried along with it so that, if there is not a sufficient space for condensation the mercury vapor flows into the prevacuum conduit; it may also occur that the prevacuum conduit gets clogged by

a large quantity of condensed mercury and that consequently the mercury entirely or partially is sucked away out of the pump.

According to the invention, an annular chamber, which enables the mercury that is condensed and eventually carried along, to be collected and to the upper surface of which the vapor jet chamber and the prevacuum conduit are led, may be arranged around the central vapor supply tube. According to the invention that portion of the prevacuum conduit that is connected to the pump, may be helically wound and be arranged within the cooling vessel of the pump.

The accompanying drawing illustrates, by way of example, some constructions of pumps according to the invention, that have two annular jet tubes arranged one after the other.

Figure 1 is a longitudinal section of a mercury vapor jet pump according to the invention, provided with two annular jet tubes and a removable central vapor supply tube.

Figure 2 is a longitudinal section of a mercury vapor jet pump according to the invention, likewise provided with two annular jet tubes and a removable supply tube, in which however, furthermore an annular vessel for collecting the mercury and a helically wound prevacuum conduit are arranged.

The pumps according to the invention may be wholly of metal; it is observed, however, that the invention can also be applied to pumps consisting wholly or partially of glass.

The pump shown in Figure 1 is provided with a mercury receptacle 1 from which a central vapor supply tube 2 rises up. A quantity of mercury 3 in the receptacle 1 may be heated in any suitable manner, for example, electrically or with the aid of gas burners. The mercury vapor produced moves upwards through the tube 2 and divides over annular jet tubes 4 and 5. The jet tube 4 is formed by the outer wall of the tube 2 and a wall 6, which forms part of a hood 7, which rests on an edge 8. The supply of mercury vapor to the jet tube 4 is regulated by a number of apertures 9 in the wall of the tube 2.

The annular jet tube 5 is formed by the outer wall of the hood 7 and the inner wall of a hood 10, which rests on the upper end of the tube 2 and is fixed to a cover 12 of the tube by means of a bolt 11. The supply of mercury vapor to the jet tube 5 is regulated by apertures 13 in the wall of the tube 2 and by slots 14 provided in the upper end of the hood 7. As the hood 7 is rotatable in the tube 2, the size of the apertures for the vapor supply to the jet tube 5 may be regulated at will.

The vapor jets coming from the jet tubes

5 and 4, carry along with them the gases of a chamber 15 and condense then on the wall of a vessel 16, which is cooled by means of a circulating cooling liquid, flowing through a cooling vessel 17 provided with supply- and discharge conduits 18 and 19. The condensed mercury flows back through a tube 20 into the receptacle 1, whilst the gases carried along by the mercury vapor, are discharged by means of a prevacuum conduit 21. The vessel to be exhausted is connected to the upper end of the tube 16.

If for some reason, however, the pump has become soiled, for example, owing to the precipitation of phosphorus carried along from incandescent lamps, near the outlet of the jet tubes 4 and 5, the pump can be easily cleaned by removing the supply tube 2 with the hoods 7 and 10.

The pump illustrated in Figure 2 operates with two annular jet tubes arranged one after the other and may be made entirely of metal.

A receptacle 31, containing a quantity of mercury 32, is provided with a cylindrical chamber 33, within which a heating device, for example an electric heating resistance can be placed. From the receptacle 31, which is surrounded by a heat insulating jacket 34, the mercury vapor flows through a common cylindrical vapor supply tube 35. At the upper end of this tube the mercury vapor is divided over annular jet tubes 36 and 37 to which apertures 38 and 39 in the wall of the tube 35 give access. The jet tube 36 is formed by the outer wall of the tube 35 and a wall 40 pertaining to a hood 41 which is slid on the upper end of the tube 35 and rests on the edge 42.

The annular jet tube 37 is formed by the outer wall of the hood 41 and the inner wall of a hood 43, which by means of a screw 44 is connected to a cover 45 of the tube 35.

Around the jet tubes a jacket 46 is arranged, which is cooled by means of a cooling liquid circulating through a cooling vessel 47 with supply- and discharge conduits 48 and 49.

The high vacuum conduit is connected to the upper end of a jacket 46 whilst a prevacuum conduit 50 passes into a helically wound portion 51, which leads to the top of an annular chamber 52. The vapor jet chamber, also, is opened out into the upper surface of the said annular chamber, whereas in the bottom of the said chamber conduits 53 and 54 end, which serve to return the condensed mercury to the receptacle 31.

The operation of the pump shown in Figure 2, is similar to that of the pump illustrated in Figure 1. In the normal operation of the pump the mercury vapor condenses substantially entirely on the wall of the tube 46. If however, for some reason or other, for example, owing to a leak in the

high vacuum conduit or to the communication of the high vacuum conduit with a vessel containing air under atmospheric pressure; gas of a high pressure has flown into the pump and if then the pressure in the pump is suddenly reduced owing to the sucking away of gases by the prevacuum conduit, an abnormally high development of mercury vapor will be produced in the manner already described, so that only part of the mercury vapor can condense on the wall of the tube 46, for a considerable part however, also flows into the helically wound portion 51 of the prevacuum conduit. This vapor condenses and flows together with any mercury carried along by the vapor, back into the chamber 52, which is large enough to contain the considerable quantity of mercury that is formed and whence the mercury can flow back into the receptacle 31. No mercury is, therefore, thrown out and the pump according to the invention offers, moreover, the advantage that it, after having been filled with a gas of high pressure, recovers itself very rapidly.

The pump according to the invention may be applied with particularly favourable results to the exhaustion of electric incandescent lamps, discharge tubes and the like. It offers special advantages, particularly for pumping devices which are so constructed that every time a considerable quantity of air flows into the pump.

The pump according to the invention may be so constructed that it is capable of operating against a comparatively bad prevacuum of, for example, 20 millimetres, whereas on the other hand it is capable of reaching a very good vacuum, for example, as is usual in high vacuum discharge tubes for wireless telegraphy. The pump may operate in series with an other high vacuum pump, which ensures therefore a very good prevacuum.

What I claim is:

1. A metal vapor jet pump comprising a boiler, a tube communicating with said boiler, at least two removable hoods arranged around said tube and forming downwardly directed annular converging jet tubes, a condensing chamber surrounding said hoods, a cooling system for cooling said condensing chamber, a connection from a vessel being evacuated to said condensing chamber and a pre-vacuum conduit from said condensing chamber to a vessel in which a low pressure is maintained.

2. A metal vapor jet pump comprising a boiler, a tube communicating with said boiler, at least two removable hoods arranged around said tube and forming downwardly directed annular jet tubes, the inner walls of said tube being non-diverging, a condensing chamber surrounding said hoods being so constructed that the hoods can be removed in upward direction, a cooling system for

cooling said condensing chamber, a connection from a vessel being evacuated to said condensing chamber and a pre-vacuum conduit from said condensing chamber to a vessel in which a low pressure is maintained. 70

3. A metal vapor jet pump comprising a boiler, a tube communicating with said boiler, at least two removable hoods arranged around said tube and forming annular jet tubes, said tube and said removable hoods being adapted to be removed from the pump without further necessity to take the latter to pieces, a condensing chamber surrounding said hoods closely, a cooling system for cooling said condensing chamber, a connection from the vessel to be evacuated to said condensing chamber and a pre-vacuum conduit from said condensing chamber to a vessel in which a low pressure is maintained. 75

4. A metal vapor jet pump comprising a boiler, a tube communicating with said boiler and resting on the upper end of said boiler, a plurality of removable hoods arranged around said tube and forming downwardly directed annular jet tubes with non-diverging wells, a condensing chamber surrounding said hoods and being so constructed that the hoods together with said tube can be removed in upward direction, a cooling system for cooling said condensing chamber, a connection from a vessel being evacuated to said condensing chamber, a pre-vacuum conduit from said condensing chamber to a vessel in which a low pressure is maintained 80 and a drain passage from said condensing chamber to said boiler. 90

5. A metal vapor jet pump comprising a boiler, a central supply tube communicating with said boiler, at least two removable hoods arranged around said tube and forming downwardly directed annular jet tubes, apertures in said central supply tube adapted to regulate the stream of metal vapor through said annular jet tubes, a condensing chamber surrounding said tubes closely, a cooling system for cooling said condensing chamber, a connection from the vessel being evacuated to said condensing chamber and a pre-vacuum conduit from said condensing chamber to a vessel in which a low pressure is maintained. 105

6. A metal vapor jet pump comprising a boiler, a central supply tube communicating with said boiler, at least two removable hoods arranged around said tube and forming downwardly directed annular jet tubes, apertures in the wall of said supply tube adapted to regulate the stream of metal vapor through said jet tubes, the apertures lying on the high vacuum side of the pump having a regulable size, a condensing chamber surrounding said hoods and so constructed that the hoods together with said supply tube can be removed, a cooling system for cooling said condensing chamber, 110 115 120 125 130

a connection from the vessel being evacuated to said condensing chamber, a pre-vacuum conduit from said condensing chamber to a vessel in which a low pressure is maintained and a drain passage from said condensing chamber to said boiler.

7. A metal vapor jet pump comprising a boiler, a tube communicating with said boiler, at least two removable hoods arranged around said tube and forming downwardly directed annular jet tubes, a condensing chamber surrounding said hoods closely, a cooling system for cooling said condensing chamber, a connection from the vessel being evacuated to said condensing chamber, said connection being so constructed that the hoods and the central supply tube can be removed without taking the pump to pieces and a pre-vacuum conduit from said condensing chamber to a vessel in which a low pressure is maintained.

8. A metal vapor jet pump comprising a boiler, a tube communicating with said boiler, at least two removable hoods arranged around said tube and forming downwardly directed annular jet tubes, a condensing chamber surrounding said tubes, a cooling system for cooling said condensing chamber, a connection from a vessel being evacuated to said condensing chamber, a pre-vacuum conduit from said condensing chamber to a vessel in which a low pressure is maintained, said pre-vacuum conduit being helically wound and enclosed by said cooling system and a drain passage from said condensing chamber to said boiler.

9. A metal vapor jet pump comprising a boiler, a tube communicating with said boiler, one or more removable hoods arranged around said tube and forming downwardly directed annular jet tubes, a condensing chamber surrounding said hoods, a cooling system for cooling said condensing chamber, an annular chamber arranged around said tube and adapted to collect the condensed mercury, a connection from a vessel being evacuated to said condensing chamber, a pre-vacuum conduit from said condensing chamber to a vessel in which a low pressure is maintained, said pre-vacuum

conduit entering the pump in the top of said annular chamber, and a drain passage from said annular chamber to said boiler.

10. A metal vapor jet pump comprising a boiler, a tube communicating with said boiler, one or more removable hoods arranged around said tube and forming downwardly directed annular jet tubes, a condensing chamber surrounding said hoods and so constructed that the hoods, together with said tube, can be removed from the pump without further necessity to take the latter to pieces, a cooling system for cooling said condensing chamber, a connection from a vessel being evacuated to said condensing chamber, and a pre-vacuum conduit from said condensing chamber to a vessel in which a low pressure is maintained, said conduit being helically wound and enclosed within said cooling system.

11. A metal vapor jet pump comprising a boiler, a central supply tube communicating with said boiler, one or more removable hoods arranged around said tube and forming downwardly directed annular jet tubes, apertures in the wall of said supply tube adapted to regulate the stream of metal vapor through said jet tubes, the apertures lying at the high vacuum side of the pump having a regulable size, a condensing chamber surrounding said hoods and being so constructed that the hoods, together with said supply tube, can be removed, a cooling system for cooling said condensing chamber, an annular chamber arranged around said supply tube and being in open communication with said condensing chamber and adapted to collect the condensed mercury, a pre-vacuum conduit from said annular chamber to a vessel in which a low pressure is maintained, said pre-vacuum conduit being helically wound and enclosed within said cooling system, and a drain passage from said annular chamber to said boiler.

In testimony whereof I affix my signature, at the city of Eindhoven this 22nd day of October, 1924.

JOHANNES MARINUS van der POEL.
